UNITED STATES PATENT OFFICE.

JAMES H. LANCASTER, OF NEW YORK, N. Y.

GRAPPLE, BUCKET, &c.

SPECIFICATION forming part of Letters Patent No. 605,489, dated June 14, 1898.

Application filed February 9, 1897. Serial No. 622,697. (No model.)

To all whom it may concern:

Be it known that I, JAMES H. LANCASTER, a citizen of the United States, and a resident of New York, in the county of New York and State of New York, have invented certain new and useful Improvements in Grapples, Buckets, &c., of which the following is a specification.

The present invention has reference to grapples, dredges, or digging apparatus, and relates more particularly to the type of construction operated on the double-chain principle—*i. e.*, one chain for opening or closing the bucket or blade sections and a second chain for suspending, raising, and lowering the grapple, dredge, or digging apparatus.

The object of the present invention is to render such a construction simple and efficient by providing a head to which the raising and lowering chain is connected and to which head is directly attached a second chain which passes around a sheave operating the opening and closing of the bucket or blade sections, the said second chain being led through the head and thence to the hoisting-drum.

A further object of the present invention is to lower the plane in which the pulley controlling the links of bucket or blade sections is located, thus dispensing with parts and making it more compact and increasing its efficiency by permitting it to operate nearer to the work.

In the drawings accompanying this specification, Figures 1, 2, and 3 are a side, end, and plan view, respectively, of a clam-shell bucket embodying one form of my invention. Figs. 4 and 5 are enlarged detail views showing in plan and side elevation the head from which the bucket is suspended and which serves for the attachment and guidance of the suspending-chain. Fig. 6 embraces enlarged detailed views of the suspending-yoke. Figs. 7 and 8 are vertical side and end elevations of a clam-shell bucket in a closed position and constructed in accordance with my present invention. Fig. 9 is a view similar to Fig. 8, but showing the bucket open. Figs. 10 and 11 are a vertical elevation and plan view, respectively, showing the improvements applied in connection with a four-

prong grapple. Figs. 12 and 13 are a vertical elevation and plan view, respectively, of a skeleton form of grapple and indicating the interchangeability of the general construction. Figs. 14 and 15 are a side and detail plan view, respectively, showing the arrangement of removable point or shoe for the blade or digging sections.

In the several constructions of grapples, buckets, dredgers, and kindred digging and excavating apparatus heretofore devised by me the bucket or blade sections were suspended from a head and caused to relatively open or close by vibrating connections with levers inwardly extending from bucket or blade sections. While such arrangement has proven highly satisfactory, I have found that it can be made more compact in its construction and efficient in its operation by pivotally attaching the upper ends of the lever connections with a sheave, around which passes the opening and closing chain. A housing or case is provided for the sheave, which guards and guides the chain passing around the sheave.

The head 1 is in the form of a casting of the shape best illustrated in Figs. 4 and 5 and comprises a body portion 2, having a circular perforation 3, and parallel extensions 4 at one side, and each of which terminates in an ear 5. Both the main parts of the extensions and the ears of the same are provided with transverse perforations 6 7, the perforations 6 being of square configuration. (See dotted lines, Fig. 4, and full lines, Fig. 5.)

Within the perforations 6 bear the squared portions of a small shaft 8, Figs. 1, 3, 8, and 9, said shaft being secured in position by means of nuts 9 and having its ends reduced to constitute engaging pivots for depending bars 10, which are pivotally connected to ears secured to the outer upper edge portions of the bucket-sections 11. It will be noted that the pair of bars 10 are hung from each pivot are slightly bent, so that they connect with the bucket-section at a point of alinement, thus affording better rigidity and regularity of construction.

The squared portions of the shaft 8 at the sides of the casting and within the pivotal engagement of the rods 10 bear in square

openings 12 in the lower ends of a lifting-yoke 13, (see Fig. 6,) centrally to which the raising and lowering chain 14 is connected.

Instead of having the bell-crank levers 15, attached by links 16 to a second casting or block in which is vertically swiveled a sheave around which is passed the opening and closing chain as heretofore constructed by me I pivotally connect said links 16 to the ends 10 of a short shaft 18, bearing in the vertical sides of a semicircular case or housing 19, the engagement of the links with the shaft being maintained by end nuts 20, as shown in Figs. 7, 8, and 9.

15 Upon the shaft 18 is mounted a sheave 21, having a grooved periphery and to a great extent contained within the case or housing 22. The bottom of the latter is centrally provided with a perforated offset or projection 22^a, which is adapted, when the bucket is in an open position, to contact with the single bearing-shaft 23, Fig. 9, upon which the bucket-sections are fulcrumed. The perforation in the offset serves to drain the case 25 or housing. The capacity and penetrating effect of the grapple is enlarged and increased by substituting the two bearing-shafts, as shown in Fig. 1.

Under some circumstances, particularly in 30 the matter of land-dredging, I prefer to plug the opening in the offset, so that oil may be introduced into the casing to lubricate the closing and opening chain while passing around the sheave.

35 A bolt 24 bears in the ears 5 5, and has secured thereto between said ears one end of the bucket-closing chain 25, which descends and passes around the sheave 21, and is thence led upward and through the circular 40 opening 3 in the head. The position of the sheave 21 within the case or housing is such that while said chain is free to move with said sheave it is positively guided thereby and is not liable to slip or become accidentally displaced therefrom.

45 The engagement of the square portions of the shaft 8 with correspondingly-shaped openings in the suspending-yoke and head insures same being maintained horizontally at all 50 times for holding the closing-chain in correct position.

The provision of the isolated circular opening 3 in the body of the head and the leading of the closing and opening chain therethrough 55 insures the proper guidance of the latter and permits it to work freely without the liability of its being interfered with by the other chain or its connection.

From the foregoing description it will be 60 seen that the head is not only of simple and inexpensive character, but in connection with the several contiguous parts constitutes a highly-efficient arrangement for securing the desired object. Moreover, the number of connections is materially reduced. Those edges 65 27 of the bucket-sections 11 which are brought in contact when the sections are closed are

provided with projecting ears 28, which overlap and maintain the sections in alinement to secure a closed joint.

70 In the clam-shell bucket described I have represented the bucket-sections 11 as being provided at their lower contiguous edges with short teeth or tines 26, detachably secured to said sections, so as to be in alternate relation, 75 and designed to impart a greater penetrating or assembling quality. These teeth or tines 26 are of such shape and so secured to the bucket-sections that when the latter are closed the teeth will be at an angle capable of permitting them to bear the weight of the apparatus should it be imposed upon the same. For many purposes, however, they are omitted.

In Figs. 1, 2, and 3 I have illustrated the shaft 18 as pivotally supporting a supplemental casting 18^x, which is provided on two of its opposite sides with ears 18^a, the links 16 pivotally depending from said ears for a movable connection with the inner ends of the arms 15, controlling the movements of the 80 bucket-sections 11 11.

The construction last described embodies a positive and simple arrangement of bucket-operating connections, in that but a single arm 15 and link 16 is all that is required for 95 each bucket-section 11. This arrangement practically secures all the advantages of the leverage system of quadruplex character disclosed in the two forms of grapples illustrated in Figs. 10 to 13, inclusive.

100 In Figs. 10 and 11 I have represented my improvements as applied to one of the latter forms of grapples constructed by me. There being, however, four blade or digging sections 11, the lever-operating links 16 are pivotally connected with pivot-bolts 17^x, bearing in ears 17^y, carried at all four sides of the case or housing, the sheave-shaft 18 in this instance merely bearing in the housing sides to support the sheave. There being an increased 110 number of depending bars 10 of special character, the head 1 is simply modified to present a horizontal rectangular frame provided on all four sides with ears carrying pivot-bolts, it still retaining the provision of the 115 circular guide-opening 3 for the closing-chain.

Figs. 12 and 13 show my improvements as being embodied in a grapple of skeleton form, the general arrangement of the head, suspending yoke-sheave 21, its housing, and the 120 lever system being substantially the same, the lever system suspending and operating a series of socketed castings 11^a, removably carrying tines, teeth, or blades 11^b, the latter having shoulders 11^c to enable them to bear 125 firmly against and be rigidly connected to the casting.

130 Referring again to Figs. 10 to 12, inclusive, and Figs. 14 and 15, it will be seen that the point of each blade or digging section is in the form of an independent shoe 29, preferably of the triangular shape illustrated in Fig. 15, the inner transverse portion of each shoe being cut away to fit snugly in a correspond-

ingly-reduced part of the casting supporting the blade-section, so that the shoe will be flush with the latter. The shoe not only has a shoulder bearing against the casting, but 5 also bears against the transverse edge of the blade-section.

To firmly secure each shoe in position, I employ a fish or tie plate 31, which is of the extended character indicated by dotted lines, 10 Fig. 15, the central part of the plate being pierced by two parallel transverse series of bolts 32, the central four of which pass through the plate 31, the shoe, the blade, and the flanges 33 of the casting. The remaining 15 bolts either pass through the plate 31 and the blade or through the tie-plate and shoe.

The removable shoe described constitutes an efficient penetrating point for each blade or digging section, its connection with the 20 main casting and section being of such a character as to be highly secure, and yet at the same time not such as to impede the penetrating capacity of each section with such point. In the event of breakage of the latter 25 another may be readily substituted.

I claim—

1. In a bucket, grapple or similar construction, the combination with a head, of bucket-sections pivotally suspended therefrom by 30 depending bars 10, movably connected to the outer upper edges of said bucket-sections, operating-levers secured to the bucket-shaft and connected by links to a sheave to be positively controlled by the rising or descending 35 movement of the same, together with a chain connected with said head, passing around the sheave and led through an independent opening in the head, substantially as set forth.

2. In a bucket, grapple or similar construction the combination with a head having an opening 3, and parallel extensions terminating in ears, the extensions having square openings 6, a suspending-yoke rigidly engaged by a shaft 8 seated in said openings 45 and an opening and closing chain connected to a pin bearing in said ears, passing around a sheave controlling the bucket-sections, and then guided through the opening 3, substantially as set forth.

3. In a bucket, grapple or similar construction, the combination with a head, of bucket-sections, pivotally suspended therefrom by depending bars 10, movably connected to the outer upper edges of the bucket-sections, 55 operating-levers positively secured to the bucket-shaft and attached to links, the upper ends of which are secured in the same horizontal plane as the journals of an operating-sheave to positively control the opening 60 and closing of the bucket-sections, together with a chain connected to said head, passed around the sheave and led through the head, substantially as set forth.

4. In a grapple, bucket or similar construction, the combination with a head, of bucket- 65 sections pivotally suspended therefrom by depending bars 10 movably connected to the outer edges of said bucket-sections, operating-levers secured to the bucket-shaft and connected by links to a sheave-containing 70 case or housing for positively opening and closing the bucket-sections, together with a chain connected with said head, passed around the sheave and led through the head substantially as set forth. 75

5. In a grapple, bucket or similar construction, the combination with bucket-sections pivotally suspended from a head and having operating-levers connected by links to a sheave-carrying housing, provided with a 80 lower projection or offset; of a chain connected to said head and passed around the sheave in the housing and led through the head, substantially as set forth.

6. In a grapple, bucket or similar construction, the combination with a head in a single piece and having square openings in which bear the square portions of a shaft 8, from 85 which the bucket-sections are suspended, of a lifting-yoke having square perforations engaged by the square portions of the shaft, together with levers 15, and connections operated by a closing and opening chain, substantially as set forth. 90

7. In a grapple, bucket or similar construction, the combination with a head in a single piece and having shaft 8, and bolt 24 the former square bearing in openings 6, said head having an opening 3, bucket-sections pivotally suspended from the shaft 8, and 100 having operating-levers connected by links to a housing carrying a sheave, a lifting yoke secured by shaft 8, and a closing and opening chain attached to the bolt 24, passed around the sheave and led upward through the opening 3, substantially as set forth. 105

8. In a grapple, bucket or similar construction, the combination with sections pivotally suspended from the head and having the operating-levers actuated by the raising and lowering chain, of a series of castings carrying the blade or digging sections and recessed as described, together with independent shoe or point sections, flush with the digging-sections and having a shoulder bearing against 110 the castings, and a fish or tie plate 31, the whole being arranged and bolted, substantially as set forth. 115

Signed at New York, in the county of New York and State of New York, this 27th day 120 of November, A. D. 1896.

JAMES H. LANCASTER.

Witnesses:

LOUIS WOHL,
N. C. FISCHER.
